FISH LURE

Earl E. Miller, Knoxville, Tenn., assignor to
Brunswick Corporation, Skokie, Ill.

Filed Sept. 26, 1972, Ser. No. 292,458

Term of patent 14 years

Int. Cl. D22—05

U.S. Cl. D22—28

Fig. 1

Fig. 2

Fig. 3

*Fig. 4**Fig. 5**Fig. 6*

FIG. 1 is a perspective view of the fish lure showing my new design;

FIG. 2 is a side elevation view thereof;

FIG. 3 is a top plan view thereof;

FIG. 4 is a bottom plan view thereof;

FIG. 5 is a front end elevation view; and

FIG. 6 is a rear end elevation view of my new design.

The broken lines for the fish hooks and their attachment to the lure are shown for illustration purposes only.

I claim:

The ornamental design for a fish lure, substantially as shown and described.
